UNITED STATES PATENT OFFICE

CHARLES Y. KNIGHT, OF PASADENA, CALIFORNIA, ASSIGNOR TO THE KNIGHT AMERICAN PATENTS COMPANY, OF CHICAGO, ILLINOIS, A CORPORATION OF DELAWARE

SLEEVE VALVE

Application filed October 6, 1922. Serial No. 592,913.

The present invention relates to a novel combination in a sleeve valve type of internal combustion engine, of a sleeve composed of such a material and so constructed that the same may be die-cast, and may also afford a materially increased means for conveying heat to the cylinder, to be dissipated thereby, by the use of water jackets or air cooling means.

One object of the invention is to provide, for example, an aluminum outer sleeve adapted to be so constructed that it may be employed between the cast iron inner sleeve of the well known Knight type of double sleeve valve internal combustion engine, so constructed as to permit relative movement of the aluminum sleeve due to variations in contraction and expansion as compared with the cast iron inner sleeve and water jacket or cylinder.

A further object of this invention is to provide a suitable longitudinal slit in the sleeve composed of the material such as aluminum which can be die-cast when a metal core is required in the die casting operation.

Various other objects are within the scope of this invention such as relate to the arrangement of the related elements or the structure, and to various details of construction and to economies of manufacture and numerous other features as will be apparent from consideration of the drawing and related description of a form of the invention, which may be preferred, in which—

Fig. 1 is an isometric view illustrating one embodiment of the invention.

Fig. 2 is an illustration of a modification thereof.

Fig. 3 is a sectional view of the adaptation of the invention to a Knight type of sleeve valve internal combustion engine.

Referring to Fig. 1 it will be seen that I have provided a cylinder 10 having suitable intake or exhaust ports 11 and 12, the cylinder being constructed of a material which may be die-cast in a mould, such as by using aluminum for example, and the same being provided in the embodiment illustrated in Fig. 1, with a longitudinal slit 15 which may serve two purposes. The slit 15 enables the

die-casting to be made when a metal core is required as will be apparent to those skilled in the art, the slit forming a means whereby the core may be removed. The slit 15 also provides means to permit expansion and contraction of the same when used with the cast iron cylinder 16, the coefficient of expansion of cast iron being different from that of aluminum.

In the modification illustrated in Fig. 3 a plurality of slits is provided, slit 15 terminating within a suitable distance from either end of the cylinder and being provided with separate additional slits 18 and 19 extending from each end of the cylinder inwardly a distance to over-lap the central longitudinal slit but spaced therefrom a suitable distance. The embodiment of the invention using a sleeve, illustrated in Fig. 3, may be used where a metal core is not needed and the slits 15, 18 and 19 may be made in each instance if desired either before or after casting. It will be noted that by employing a metal which may be die-cast the production of a Knight type of engine may be greatly facilitated and at the same time a metal of this character forms a more ready means of heat dissipation.

It is apparent that, within the spirit of the invention modifications and different arrangements may be made other than as herein disclosed, and the present disclosure is illustrative merely, the invention comprehending all variations thereof.

I claim:

1. In a sleeve valve type internal combustion engine, a cylinder, a piston and inner sleeve of cast iron and an outer sleeve of a material which may be die-cast in a mold, said outer sleeve being located between the inner sleeve and the cylinder, said cylinder, inner sleeve and outer sleeve having suitable intake and exhaust ports located therein, said outer sleeve being longitudinally slit to provide for contraction and expansion thereof at a different rate with respect to the contraction and expansion of the contacting surfaces.

2. In a sleeve valve type internal combustion engine, a cylinder, a piston, an inner

sleeve, said piston and inner sleeve being of a metal other than aluminum and an outer sleeve of aluminum provided with a longitudinal slit to permit transverse contraction and expansion, said cylinder, inner sleeve and outer sleeve having suitable intake and exhaust ports located therein.

3. In a sleeve valve type internal combustion engine, a cylinder, a piston, an inner sleeve of one material and an outer sleeve of a different material, provided with a longitudinal slit to permit transverse contraction and expansion, said cylinder, inner sleeve and outer sleeve having suitable intake and exhaust ports located therein.

4. In an internal combustion engine of the sleeve valve type, the combination of a cylinder and reciprocating inner and outer sleeves coaxial therewith, said outer sleeve being made of material having a higher coefficient of expansion than the material of said inner sleeve, and means for permitting the self-adjustment of said outer sleeve to compensate for such difference in expansion.

5. In an internal combustion engine of the sleeve valve type, the combination of a cylinder and reciprocating inner and outer sleeves coaxial therewith, said outer sleeve being made of light weight material having a higher coefficient of expansion than said inner sleeve, and means for permitting the self-adjustment of said outer sleeve to compensate for such difference in expansion.

6. In an internal combustion engine of the sleeve valve type, the combination of a cylinder and reciprocating inner and outer sleeves coaxial therewith, said cylinder and inner sleeves being made of cast iron, and said outer sleeve being made of aluminum, and means for permitting the self-adjustment of said outer sleeve to compensate for the different rates of expansion of said sleeves.

7. In an internal combustion engine of the sleeve valve type, the combination of a cylinder and reciprocating inner and outer sleeves coaxial therewith, said outer sleeve being made of material having a higher coefficient of expansion than said inner sleeve and being longitudinally slit to permit the self-adjustment of said outer sleeve to compensate for such difference in expansion.

8. In an internal combustion engine of the sleeve valve type, the combination of a cylinder and reciprocating inner and outer sleeves coaxial therewith, said cylinder and inner sleeve being made of cast iron and said outer sleeve being made of aluminum and longitudinally slit to permit the self-adjustment of said outer sleeve to compensate for the different rates of expansion of said inner and outer sleeves.

In testimony whereof, I affix my signature.
CHARLES Y. KNIGHT.
